UNITED STATES PATENT OFFICE.

GIOVANNI EMANUELE ELIA, OF WESTMINSTER, LONDON, ENGLAND, ASSIGNOR TO
VICKERS LIMITED, OF LONDON, ENGLAND.

SUBMARINE MINE.

Application filed September 25, 1924. Serial No. 739,824.

To all whom it may concern:

Be it known that I, GIOVANNI EMANUELE ELIA, a subject of the King of Italy, of Vickers House, Broadway, Westminster, in the county of London, England, have invented certain new and useful Improvements in or Relating to Submarine Mines, of which the following is a specification.

This invention relates to submarine mines of the kind in which auxiliary contact devices are provided (in addition to those usually furnished on the flotation chamber), said devices being carried on the mooring cable itself or on auxiliary conductors attached to the flotation chamber or attached to both the flotation chamber and the mooring cable or anchor, the arrangement being such that the explosion of the mine is produced either by contact with the flotation chamber itself or with any one of the aforesaid contact devices.

According to the present invention the auxiliary contact devices are constituted by cables or conductors on which hooks or their equivalent are mounted at suitable distances apart along its length, said hooks when struck or dragged by a passing submarine, the tow line of a paravane, or the like, being adapted to move relatively to said cables or conductors and to actuate contact devices which serve to complete an electric circuit and explode the mine. To this end the auxiliary contact devices may be constituted by cables or conductors on which a flexible and slideable sleeve is mounted to which the aforesaid hooks are attached, said hooks when struck by a passing submarine or the like being adapted to cause relative movement to take place between the sleeve and the cable or conductor. On the sleeve being moved a striker provided in the flotation chamber may be adapted to be cocked and thereafter released to produce the rupture of a tube containing an electrolyte, which latter is employed to energize a pile battery, the current from which actuates an electric detonator forming part of the firing gear. A soluble plug may be provided in order to prevent movement of the sliding sleeve or actuation of the striker until the lapse of a predetermined interval after launching. In cases where the auxiliary cable is attached to the flotation chamber and supported by means of a float, the latter may be provided with contact devices such

as horn batteries of similar construction to those on the flotation chamber or mine proper and the cable may be provided within its interior with electric conductors which are in circuit with the said horn batteries and with the firing gear of the mine, the arrangement being such that, on one of the horn batteries on the float being struck, the battery is energized and the firing gear of the mine is actuated. The aforesaid arrangement may be used in combination with a cable upon which a sliding sleeve is provided having contact devices mounted thereon in the manner above described, the conductors in such cases being preferably positioned within the core of the said cable.

In order that the said invention may be clearly understood and readily carried into effect the same will now be described more fully with reference to the accompanying drawings which show by way of example a submarine mine constructed according to the present invention, and in which:—

Figure 1 is an elevation of the complete mine and

Figure 2 is a plan.

Figure 3 is a sectional elevation of the complete mine showing the same in position on the launching rails, and

Figure 4 is a section through the sinker showing part of the plummet release and pawling gear.

Figures 5 and 6 are sectional views on an enlarged scale showing, respectively, the details of construction of the lower and upper sections of the auxiliary firing gear.

Figure 7 is a view showing the disposition of the parts of the mine after the latter has been launched and during the paying out of the mooring cable from the sinker.

Figure 8 is a diagrammatic view showing a submarine boat striking the upper section of the auxiliary firing gear; in this position the hooks on the cable will catch on the external projections on the hull of the submarine and the pull on the cable will operate the auxiliary firing battery in the mine.

Figure 9 shows diagrammatically a surface vessel striking one of the horns on the upper float. In this instance the bending of the horn struck by the vessel will energize its battery and fire the detonator of the mine through the contact circuit which is located within and forms the core of the length

of cable extending between the float and the mine.

Figure 10 is a diagrammatic view showing the auxiliary firing gear acting as an antiparavane defence. When the towline of a paravane strikes the upper section of the auxiliary firing gear the wire will jam under one of the cable hooks (which are especially shaped for this purpose) and exercise 10 a pull on the cable which will act to fire the mine. Should the firing cable be struck at a point on the paravane wire near the paravane, and so possibly slide into the paravane cutter before jamming, there will be sufficient 15 pull transmitted to the cable to fire the mine before the cutting of the cable could be effected. Owing to the heavy explosive charge carried within the flotation chamber and with a paravane towed even at 20 a distance of 50 metres from the vessel, the latter would still be within the effective range of the mine even if the paravane wire struck the cable at its extreme range. The maximum spread, however, of the paravane 25 from the centre line of a vessel, which is at present considered practicable is about 35 metres. Consequently and by reason of the present invention the paravane is rendered useless as a means of protecting a ship 30 against submarine mines. On the contrary the use of the paravane will only serve to increase the effectiveness of the mine, as mines fitted with the auxiliary firing gear and spaced at 60 metres apart will form a 35 continuous firing zone for a surface vessel carrying paravanes with a 30 metres spread on each side of its fore and aft line.

Figure 11 shows a small buoy connected to the upper float containing a switch which 40 is connected to the firing circuit in the float. This buoy when used during trials will enable the mine circuits to be made safe if it is desired to sweep or lift the mine. The float can be picked up by a small boat and the 45 buoy opened to operate a switch, which when actuated short-circuits the circuit from the float to the mine. If any of the mine horns are broken in sweeping or lifting the mine the short-circuited circuits to the switch 50 form a shunt on the circuit from the mine battery to the detonator, with a resistance relatively smaller than that of the battery-detonator circuit, so that the current flowing through the detonator is so reduced as to be 55 less than the minimum required to fire the detonator.

A is the casing of the flotation chamber or mine proper which is made strong enough to withstand safely submersion at a depth 60 of say 100 metres. A¹ is the charge case which, in the example shown, is adapted to contain 300 kg. of explosive, and which is removable through a flange in the top of the mine. A tube B is fixed horizontally 65 through the middle of the charge case, forming

ing a chamber into which is inserted a closed tube C fixed to a flange D the tube C being inserted through the side of the mine and forming a container for the primer tube E. When the tube E is pushed home, a 70 spring F located at the end of the closed tube C is compressed and the tube is held in position by a trigger G operated by means of a Bowden wire connection H from the mooring spindle H¹ of the mine. J is an 75 electric detonator which is carried on the end of a tube J¹ fixed to a detonator holder K which makes contact with the leads K¹, K² of the battery circuits. In view of this arrangement and when the mooring spindle H¹ moves to operative position under the influence of the tension on the mooring cable acting through the pivoted lever H₂, the primer tube E is released, and the spring F pushes it into contact with the 80 detonator J. The firing mechanism plate L in the bottom of the mine is fitted with a safety switch H¹, H², H³ of the type described in our pending United States application Serial No. 661,754 which controls the 85 battery circuits, and which is operated by the buoyancy of the mine, subsequent to the operation of a soluble plug safety device (not shown), while, as described above, the movement of the mooring cable spindle H¹ 90 which forms part of the safety device, also actuates the Bowden wire connection H and allows the spring F to push the primer E into contact with the detonator J. In the example shown, the casing A of the flotation chamber or mine proper is provided with six horn batteries A³, A⁴ of the well known Hertz type. M is a cylindrical skirt 95 fixed to the lower part of the casing A which is seated upon the sinker N. O is a float 100 which supports the upper auxiliary firing cable O¹ and which is provided with four horn batteries O², also of the Hertz type which, by leads K³, K⁴, an electric cable O³, which forms the core of the auxiliary cable 105 O¹, and leads K², K¹ are connected to the detonator circuit K¹, K¹ of the mine.

P is the mooring rope which is carried on a horizontal drum P¹ formed of two steel 110 pressings, riveted together and connected to a central hub P² which runs on bearings P³, P⁴ on a central pillar P⁶ which also serves to connect together the upper and lower covers P⁴, P⁵ which, together with the circumferential plate N¹, form a watertight 115 casing for the drum P¹ and mooring rope P. The circumferential plate N¹ fits closely around the rim of the mooring rope drum P¹ so as to render it impossible for the mooring rope P to leave the sides of the drum P¹. Q is the plummet which is positioned, before launching of the mine, on the side of the sinker N, and is located directly over one of the launching rails R¹ by means of 120 an arrangement of links S and a roller S¹ 125

such that it is normally supported by the rail R^1 , but is free to drop immediately the sinker N leaves the rails R^1 , R^2 , under the control of a dashpot mechanism which delays its release until after the mine and sinker combination returns to the surface. The plummet Q is connected to the sinker N by the requisite length of chain or cable, one end of the chain being attached to a lever R in such manner that the plummet Q hangs vertically under the centre line of the sinker N during the descent of the sinker to the sea bed, as shown at Figure 7. The weight of the plummet Q acting on the lever 10 R , holds the pawling lever T out of action against the influence of a strong spring T^1 , until the weight of the plummet is relieved by contact with the sea bed whereupon the spring T^1 forces the pawling lever T into engagement with one of the notches U^1 on an annular plate U which is riveted to the upper part of the mooring rope drum P and thereby locks the drum P^1 . The pawling gear (lever T , spring T^1 , etc.,) is initially 15 held out of action by an antivibration gear V operated by a tooth gear drive V^1 , V^2 from the drum P^1 until the sinker N is well separated from the mine A . After the pawling gear operates, it is positively locked by 20 a spring actuated locking lever T^2 . The flotation chamber A is released from the sinker N by the dropping of the plummet Q which actuates the release link W . On the mine A separating from the sinker N a flooding 25 valve (not shown) is opened which allows water to enter the sinker casing N and so destroy its buoyancy. The speed of descent of the sinker N is regulated by a pair of brakes constituted by spring controlled 30 plungers X which produce the requisite resistance by alternately rising and falling over detents acting on teeth X^1 on the annular plate U . The mooring rope P is led through the outside of the sinker casing over 35 a rubbing plate Y at a sufficient distance from a pulley Y^1 to give a good angular lead. Between the slot Y^3 where it comes out of the casing and the pulley Y^1 the rope P^1 is enclosed by a cover plate Y^2 . A heavy anchor R^3 is connected to the sinker by a universal joint, and freed when the mine leaves 40 the sinker. A considerable portion of the total weight of the sinker is made up by cast iron balance weights Z bolted inside the sinker in such a position that their weight 45 tends to keep the sinker vertical when sinking. A connection Z^1 is provided on the side of the casing for coupling up a hose to wash through the sinker after trials. Mud holes 50 Z^2 with detachable cover plates Z^3 are provided in the bottom plate of the casing. The rail wheels R^2 are fixed underneath the sinker N and their spacing can be made to 55 suit any desired spacing of the rails R^1 . 60 The auxiliary firing apparatus comprises

a cable O^1 extending 50 metres above the mine and another cable O^2 extending 50 metres below the mine, the latter being, in the example shown, constituted by a specially constructed portion of the mooring cable P . On the cables O^1 , O^2 are fixed hooks 1, 1 adapted to catch on projections on the outside of a submarine boat, or on the tow line of a paravane, etc., with the result that an upward pull is transmitted by 70 the cables to mechanism (hereinafter described) on the flotation chamber A . This pull effects the release of a spring operated striker, which fractures a glass tube containing electrolyte, which in turn energizes 80 a battery in the same manner as in the horn and battery units. The auxiliary batteries are connected to the firing circuit of the mine in the same manner as the horn batteries. The cable O^1 of the upper firing 85 apparatus is supported by the float O which in the example shown has a net buoyancy of 220 kg. The pull due to the buoyancy of the float O is transmitted directly to the flotation chamber A by means of an inner 90 mooring cable 2, the core of which contains the insulated wires O^3 , connecting the horn batteries O^2 of the float O through the leads K^2 , K^3 to the firing circuit of the mine. The inner core O^1 of the cable 2, 95 passes at its upper end through a watertight gland O^4 into the float O and at its lower end through a watertight gland O^5 into the flotation chamber A . The auxiliary firing apparatus on both the cables O^1 100 and O^2 comprises a flexible metallic tubular sleeve 2^a surrounding the cable 2 and the mooring cable O^1 . The sleeve 2^a slides freely on the cables 2 and P , and the interior space between the sleeve 2^a and the cables P and O^1 is packed with grease, to ensure easy working, and the parts rendered watertight by a rubbered outer covering. The hooks 1, 1 are attached to the outside of the sleeve 2^a by clamps 3, 3 and are spaced 105 at suitable intervals apart of, say, one metre. In the case of the auxiliary cable O^1 , the upper end of the sleeve 2^a is connected to the float O by a concertina-like piece 5^a which excludes water but permits the sleeve 2^a to move upwards freely when pulled by a submarine boat etc. The lower end of the sleeve 2^a is also connected to a casing A^4 on the top of the flotation chamber A by a concertina-like piece 5^b . The lower end of the 110 sleeve 2^a is connected to mechanism 6 which when the sleeve 2^a is actuated, retracts the striker 6^a and compresses the striker spring 6^b . When the balls 7, which are accommodated with a groove 7^a in the striker rod, 115 come opposite the openings 8, 8 they move out laterally, thus releasing the striker 6^a from the fixed part 7^b and the reaction of the spring 6^b impels the striker into contact with the glass tube 9 located above the bat- 120

tery 10 thus releasing the electrolyte contained within the said tube 9 and energizing the battery 10 the current generated in which passes through the leads h^1 , h^1 to the switch of the electric detonator K in well known manner. A rubber diaphragm 10' is provided for the purpose of making a watertight connection for the parts of the firing mechanism. A soluble plug (not shown) is also provided which only permits the firing mechanism to be operated after the mine has been launched and is moored to the sea bed. The lower auxiliary firing gear, which is of substantially similar construction to that of the upper auxiliary firing gear, also comprises a flexible metallic sleeve 2^a surrounding the upper part of the mooring cable P. The mooring cable P extends through the center of said sleeve 2^a and is connected at its upper end by means of an eye 13 to the pivoted lever H² which is mounted upon the flotation chamber A. A rubberized outer covering is also provided and surrounds the sleeve 2^a and the space between the sleeve 2^a and the cable P is also packed with grease to ensure that the sleeve 2^a will slide easily thereon. The hooks 1, 1 provided on the exterior of the sliding sleeve 2^a are of similar construction to those already described in connection with the upper auxiliary firing gear, as are the concertina-like connections 5^a, 5^b at both its upper and lower ends which allow free sliding movement of the sleeve 2^a upon the cable P, while keeping water out from the interior of the said sliding tube 2^a. At its upper end the sliding sleeve 2^a is connected at 16 to an extension 17 of the striker rod 5 by means of a lever 14 pivotally attached at 15 to a lug 16 on the lower part of the mine easing. When the sliding sleeve 2^a is raised owing to contact being established between the hooks 1, 1 and a submarine, the towing wire of a paravane or the like, the sleeve 2^a will be raised thus depressing the end of the pivoted lever 14 which is connected at 16 through the part 17 with the striker rod 5. The parts of the striker release mechanism are of similar construction to those already described in connection with the upper auxiliary firing gear, but in this case the soluble plug, which restrains the firing gear from actuation until after the mine is launched is shown at 18. On the mine being launched water enters through the opening 18' and acts on the soluble plug 18, thus dissolving the same and releasing the striker. A rubber diaphragm 10 is also provided for the purpose of keeping the parts watertight.

What I claim and desire to secure by Letters Patent of the United States is:—

1. A submarine mine comprising an anchoring cable, a sleeve slidably mounted on said anchoring cable, hooks carried by said

sleeve, said hooks when struck being adapted to cause relative movement to take place between said sleeve and said anchoring cable, the movement of said sleeve being adapted to actuate a striker and explode the mine. 70

2. A submarine mine comprising an anchoring cable, a sleeve slidably mounted on said anchoring cable, hooks carried by said sleeve, said hooks when struck being adapted to cause relative movement to take place between said sleeve and said anchoring cable, the movement of said sleeve being adapted to actuate a striker and explode the mine, and a soluble plug which prevents 80 actuation of the sliding sleeve until the lapse of a predetermined interval after launching. 75

3. A submarine mine comprising a flotation chamber, a sinker, a mooring cable 85 connecting said flotation chamber to said sinker, a sleeve slidably mounted upon said mooring cable, projecting contact devices carried by said sleeve, which when struck, cause said sleeve to move relatively to said mooring cable, a striker within said flotation chamber, the movement of said sleeve being adapted to actuate said striker so as to fire the mine. 90

4. A submarine mine comprising a flotation chamber, a sinker, a mooring cable connecting said flotation chamber to said sinker, a sleeve slidably mounted upon said mooring cable, projecting contact devices carried by said sleeve, which when struck, 100 cause said sleeve to move relatively to said mooring cable, a striker within said flotation chamber, the movement of said sleeve being adapted to cock and thereafter release the striker so as to fire the mine. 105

5. A submarine mine comprising auxiliary contact devices constituted by a float attached by a cable to the flotation chamber, said float being provided with horn batteries connected through leads to the 110 firing circuit of the mine, said horn batteries when struck being adapted to generate an electric current which produces the explosion of the mine.

6. A submarine mine comprising auxiliary firing apparatus constituted by a cable located between the flotation chamber and a supporting float, said cable containing electric conductors which are in circuit with horn batteries carried by the float attached to the upper end of the cable, the cable being also provided with a flexible sleeve on which hooks are mounted the construction and arrangement of the parts being such that on either or both the horn batteries or the hooks being struck the mine is exploded. 115

7. A submarine mine comprising auxiliary firing apparatus constituted by a cable or conductor surrounded by a sleeve 130

carrying hooks or the like, said sleeve being provided at its upper and lower ends with concertina-like parts which allow relative movement to take place between said sleeve and the interior cable or conductor, the arrangement of the parts being such that when the hooks are struck the sleeve is moved and a striker is first cocked and thereafter released to produce the rupture 10 of a tube containing an electrolyte which energizes a pile battery the current from which actuates the firing gear of the mine.

8. A submarine mine as claimed in claim 6 in which a soluble plug is provided in 15 order to prevent actuation of the sliding sleeve until the lapse of a predetermined interval after launching.

9. A submarine mine comprising a sliding sleeve which surrounds the mooring 20 cable and is connected to the striker mechanism through the intermediary of a pivoted lever, said sleeve on relative movement taking place between the same and the interior cable being adapted to first retract the 25 striker and thereafter release the same to effect the explosion of the mine.

10. A submarine mine of the kind set forth provided with a spring pressed primer which is normally held out of contact with 30 the detonator until after the mine is

launched, a Bowden wire control being provided which is adapted to be actuated after launching of the mine by the increased tension on the mooring spindle so as to withdraw a locking bolt and allow the 35 primer to move into contact with the detonator.

11. A submarine mine comprising a flotation chamber and an anchor, a drum within said anchor, a mooring cable upon said 40 drum, said anchor being adapted to move from a horizontal position to a vertical position after launching of the mine under the influence of the plummet for the purpose 45 specified.

12. A submarine mine of the kind set forth, comprising an anchor containing a winch drum rotatable about a centrally disposed pivot and a ratchet plate which is adapted to be engaged and locked by a 50 pawl, on the plummet which is connected to one end of said pawl striking the sea bed, said pawl being normally prevented from engaging with said ratchet until the expiration of a predetermined interval after 55 launching by means of toothed gearing and an arrangement of links and levers actuated by a toothed wheel from the said centrally located spindle.

GIOVANNI EMANUELE ELIA.
